 ESTERS OF QUATERNARY 2-HYDROXY METHYL
PIPERIDINIUM COMPOUNDS

Kurt Flick, Stolberg, Rhineland, and Heinrich Mueckter, Aachen, Rhineland, Germany, assignors, by mesne assignments, to the firm Protochemie AG, Glarus, Glarus, Switzerland, a corporation of Switzerland

6 Claims. (Cl. 260—293.4)

The present invention relates to new esters of quaternary ammonium compounds and more particularly to new carboxylic acid esters of 2-hydroxy methyl piperidinium compounds, and to a process of making and using 15

It is one object of the present invention to provide new and valuable carboxylic acid esters of 2-hydroxy methyl piperidinium compounds which have a high spasmolytic acitivity and a surprisingly low toxicity.

Another object of the present invention is to provide a simple and effective process of producing such new carboxylic acid esters of 2-hydroxy methyl piperidinium compounds.

A further object of the present invention is to provide highly effective and well tolerated spasmolytic compositions containing, as active agent, such new carboxylic acid esters of 2-hydroxy methyl piperidinium compounds.

Still another object of the present invention is to provide a simple and effective process of relaxing spastic conditions.

Other objects of the present invention and advantageous feaatures thereof will become apparent as the description proceeds.

In principle the new and valuable spasmolytic compounds according to the present invention are carboxylic acid esters of 2-hydroxy methyl piperidinium compounds of Formula I

(I)

wherein

R₁ represents hydrogen, alkyl, aralkyl, cycloalkyl, aryl, or heterocyclic radicals which may be substituted;

R₂ represents hydrogen, alkyl, cycloalkyl, aralkyl, or aryl radicals which may be substituted;

R₃ represents an aryl or a cycloalkyl radical which may be substituted;

R₄ represents hydrogen, a hydroxyl group which may be esterified, or halogen;

R₅ represents an alkyl radical which may be substituted; and

An indicates an anion.

The new compounds of Formula I are very effective spasmolytic agents of a surprisingly/low toxicity. The LD₅₀, i.e. the dose after administration of which 50% of the test animals die, is, for instance, for the metho-

2

sulfate of (1-methyl piperidyl-2)-methyl benzilate of Formula II

(II)

10 which compound will be designated hereinafter as "compound A" on oral administration about 1.900 mg./kg. of mouse body weight or respectively, about 3.700 mg./kg. of rat body weight, and on subcutaneous administration 350 mg./kg. of mouse body weight or respectively, more than 2.000 mg./kg. of rat body weight. The amount of Compound A needed for relaxation of the spastic condition of the isolated surviving rat ileum caused by barium chloride is only one fiftieth of the required amount of papaverine. The spastic condition of the isolated surviving rat ileum caused by acetylcholine is relaxed by Compound A in a concentration of 0.002 mg./l. Approximately, the same results are obtained, for instance, by testing the benzilates of (1-n-butyl piperidyl-2)-methanol methiodide or (1-n-octyl piperidyl-2)-methanol methobromide.

These results could be confirmed for Compound A in clinical investigations on humans. Side-effects were not observed when the compound was given orally, rectally, subcutaneously, or intramuscularly, respectively. In adults good spasmolytic effects were observed after oral or rectal administration of 20 mg. of Compound A or after intramuscular administration of 1 mg. of Compound A. Cases of spastic bronchitis, of gastritis and/or gastric ulcer, spastic colitis, spasms of the gall-bladder and bile-ducts, renal colics, and others were treated with these new agents.

The new compounds of Formula I are prepared for instance, by the following methods:

40 (A) A compound of Formula III

(III)

50 wherein R₁, R₂, R₃, and R₄ have the same meaning as indicated in Formula I, is reacted, preferably in the presence of a solvent, with a compound of Formula IV

wherein

55 R₅ has the same meaning as indicated in Formula I, and X₁ represents halogen or a sulfuric acid ester group.

(B) A compound of Formula V

(V)

65 wherein R₂, R₃, R₄, and R₅ have the same meaning as indicated in Formula I, is reacted, if required, while heat-

ing and preferably in the presence of a solvent with a compound of Formula VI

wherein R_1 has the same meaning as indicated in Formula I, and

X_1 has the same meaning as indicated in Formula IV.

(C) A compound of Formula VII

wherein R_1 , R_5 , and An have the same meaning as indicated in Formula I, and

Hal represents halogen,

is reacted with an acid of Formula VIII

wherein R_2 , R_3 , and R_4 have the same meaning as indicated in Formula I, in the presence of a compound capable of binding hydrogen halide or with a salt of such an acid of Formula VIII, if desired, in presence of a solvent and preferably while heating.

(D) A compound of Formula IX

wherein R_1 , R_5 and An have the same meaning as indicated in Formula I, is reacted with a compound of Formula X

wherein R_2 , R_3 , and R_4 have the same meaning as indicated in Formula I, and

Y represents halogen or an esterified hydroxyl group,

either in the absence or in the presence of an inert organic solvent, preferably in the presence of a compound capable of binding the acid formed in the reaction, for instance, in the presence of a tertiary amine, an alkali metal carbonate, an alkali metal bicarbonate, or the like.

The anion present in the compound of Formula I resulting from proceeding according to one of the processes described herein above can be replaced by another suitable anion. For this purpose, for instance, a halide of the resulting quaternary ammonium compound may be reacted with a suitable silver salt. In this manner compounds of Formula I can be produced the preparation of which is difficult when following the processes described above.

The new compounds of Formula I contain at least one carbon atom which is asymmetrically substituted. Therefore, they can be obtained as racemic mixtures or in their optically active forms. In order to prepare said compounds in their optically active forms, optically active starting materials may be used in the processes described hereinabove. However, the new optically active compounds may also be prepared first in their racemic form which is subsequently resolved to their optically active isomers.

The following examples serve to illustrate the present

invention without, however, limiting the same to the contents of said examples.

Example 1

5 5 g. of (1-methyl piperidyl-2)-methyl benzilate are suspended in 10 ml. of acetonitrile. A solution of 6.4 g. of methyliodide in 20 ml. of acetonitrile is added thereto. The reaction mixture is allowed to stand at 30-40° C. for 48 hours whereafter the solvent is distilled off in a vacuum. The residue is recrystallized from a mixture of acetone and petroleum ether, whereby the methiodide of the starting material is obtained in a yield of 70% of the theoretical yield. Melting point: 130-132° C.

15

10 A mixture of 5 g. of (1-methyl piperidyl-2)-methyl benzilate, 7 g. of ethyliodide, and 30 ml. of dry acetone is refluxed for 6 hours. The residue obtained on distilling off the solvent is recrystallized from a mixture of 20 ethanol and petroleum ether. The resulting ethiodide of the starting material is obtained in a yield of 60% of the theoretical yield. It melts at 151-154° C.

Example 2

15 A mixture of 5 g. of (1-methyl piperidyl-2)-methyl benzilate, 7 g. of ethyliodide, and 30 ml. of dry acetone is refluxed for 6 hours. The residue obtained on distilling off the solvent is recrystallized from a mixture of 20 ethanol and petroleum ether. The resulting ethiodide of the starting material is obtained in a yield of 60% of the theoretical yield. It melts at 151-154° C.

Example 3

20 25 A mixture of 7.6 g. of dimethylsulfate and 15 ml. of acetone is added to a solution of 10.2 g. of (1-methyl piperidyl-2)-methyl benzilate in 50 ml. of dry acetone. The reaction mixture is allowed to stand at 30-40° C. for 2 days. The precipitated crystals are filtered off and 30 recrystallized from a mixture of acetone and ethanol while heating and adding petroleum ether to the warm solution. The resulting methosulfate is the "compound A" mentioned hereinabove. It melts at 134-135° C. Yield: 92% of the theoretical yield.

35

Example 4

40 45 A solution of 5.7 g. of methyliodide in 10 ml. of acetone is added to a solution of 7.6 g. of (1-n-butyl piperidyl-2)-methyl benzilate in 60 ml. of dry acetone. The reaction mixture is allowed to stand at 30-40° C. for 24 hours. Petroleum ether is added thereto until the mixture becomes turbid. The precipitate formed gradually after standing for 1 day to 2 days is filtered off by suction and is recrystallized twice from a mixture of acetone and ethanol while heating and adding petroleum ether to the warm solution. The resulting methiodide of the starting material melts at 174-175° C. The yield is about 40% of the theoretical yield.

50

55 60 A solution of 4.8 g. of methylbromide in 25 ml. of absolute ethanol is added to a solution of 11 g. of (1-n-octyl piperidyl-2)-methyl benzilate in 40 ml. of dry acetone. After standing for 2 days at 30-40° C., the solvents are removed by distillation in a vacuum. The residue is recrystallized from a mixture of acetone and ethanol while heating and adding petroleum ether to the warm solution whereby the methobromide of the starting material which melts at 183-184° C. is obtained in a yield of 58% of the theoretical yield.

Example 5

65 70 A solution of 5.7 g. of methyl iodide in 10 ml. of acetone is added to a solution of 8.6 g. of (1- β -phenyl ethyl piperidyl-2)-methyl benzilate in 25 ml. of dry acetone. After standing at 30-40° C. for 2 days, the reaction mixture is freed of the solvent by distillation in a vacuum. The residue is recrystallized from a mixture of acetone and ether whereby the methiodide of the starting material is obtained in a yield of 70% of the theoretical yield. Melting point: 170-173° C.

Example 6

75 80 A solution of 5.7 g. of methyl iodide in 10 ml. of acetone is added to a solution of 8.6 g. of (1- β -phenyl ethyl piperidyl-2)-methyl benzilate in 25 ml. of dry acetone. After standing at 30-40° C. for 2 days, the reaction mixture is freed of the solvent by distillation in a vacuum. The residue is recrystallized from a mixture of acetone and ether whereby the methiodide of the starting material is obtained in a yield of 70% of the theoretical yield. Melting point: 170-173° C.

Example 7

85 90 6 g. of the (1-methyl piperidyl-2)-methyl ester of diphenyl acetic acid are dissolved in 20 ml. of absolute

methanol. 15 g. of a 25% solution of methyl bromide in methanol are added thereto. The reaction mixture is allowed to stand at room temperature for one week. After concentrating the reaction mixture by distillation in a vacuum, the residue is triturated with absolute ether. The resulting precipitate is filtered off by suction and is recrystallized twice from a mixture of absolute ethanol and absolute ether. The methobromide of the starting material is obtained in a yield of 39% of the theoretical yield. Melting point: 176-178° C.

Example 8

A mixture of 4.9 g. of ethyl bromide and 10 ml. of acetone is added to a solution of 5 g. of (1-methyl piperidyl-2)-methyl benzilate in 25 ml. of dry acetone. The reaction mixture is allowed to stand at room temperature for 6 days. After concentrating the reaction mixture by distillation in a vacuum, the residue is recrystallized first from a mixture of acetone and petroleum ether and then from a mixture of absolute ethanol and petroleum ether. The ethobromide of the starting material is thereby obtained in a yield of 46% of the theoretical yield. Melting point: 185-187° C.

Example 9

A mixture of 10.2 g. of (1-methyl-piperidyl-2)-methyl benzilate, dissolved in 50 ml. of acetone, and 25 ml. of a 25% solution of methylbromide in methanol is allowed to stand at room temperature for three days. Petroleum ether is added thereto until the solution becomes turbid. The precipitate formed after standing overnight in an ice box, is filtered off, dried by exposure to the air, and recrystallized from a mixture of absolute ethanol and petroleum ether. After drying by exposure to the air, the hydrate of the methobromide of the starting material is obtained in a yield of 66% of the theoretical yield. Melting point: 108-109° C.

Example 10

3 g. of freshly prepared silver chloride are added to a solution of 4.8 g. of (1-methyl piperidyl-2)-methyl benzilate methiodide in 20 ml. of methanol. The mixture is shaken for 10 minutes and then allowed to stand in the dark for 24 hours. After filtering off the precipitate by suction, the filtrate is freed of solvent by distillation in a vacuum. The residue is recrystallized from a mixture of acetone and ethanol while heating and adding petroleum ether to the warm solution whereby (1-methyl piperidyl-2)-methyl benzilate methochloride, melting at 115-118° C. is obtained in a yield of 64% of the theoretical yield.

Example 11

Methyl bromide is passed at room temperature into a solution of 5 g. of the ester of α -cyclohexyl phenyl glycolic acid and (1-methyl piperidyl-2)-methanol in 50 ml. of acetone until 12 g. of methylbromide have been absorbed. Colorless crystals start to precipitate during introduction of the methylbromide. The reaction mixture is cooled in an ice bath and the precipitated crystals are filtered off by suction. Thereby, the methobromide of the starting material is obtained in a yield of 63% of the theoretical yield. After recrystallization from a mixture of acetone, ethanol, and petroleum ether, its melting point is 197-199° C.

Example 12

A mixture of 5.4 g. of 1-methyl-2-hydroxy methyl-piperidine methiodide, 4.6 g. of diphenyl acetylchloride, 2 g. of triethylamine, and 100 ml. of dry dioxane is refluxed for three hours while stirring. After standing overnight, the solvent is decanted off and the residue is recrystallized from a mixture of ethanol and petroleum ether. Thereby, the (1-methyl piperidyl-2)-methyl diphenylacetate methiodide is obtained in a yield of 54% of the theoretical yield. Melting point: 165-168° C.

Example 13

4.9 g. of 1-methyl-2-chloro methyl piperidine methobromide and 5.3 g. of potassium benzilate are added to 100 ml. of absolute ethanol. The mixture is refluxed for two hours while stirring and is then filtered while still hot. The filtrate is evaporated to dryness in a vacuum and the resulting residue is recrystallized from a mixture of acetone, ethanol, and petroleum ether whereby (1-methyl piperidyl-2)-methyl benzilate methobromide melting at 160-162° C. is obtained in a yield of 35% of the theoretical yield.

In place of the benzilic acid esters used in Examples 1 to 6, 8 and 9, the diphenyl acetic acid ester used in Example 7, and the α -cyclohexyl phenyl glycolic acid ester used in Example 11, there may be employed other acid esters of 1-alkyl-2-hydroxy methyl piperidines 1-phenyl lower alkyl-2-hydroxy methyl piperidines such as the corresponding esters with α -chloro diphenyl acetic acid or mandelic acid.

In place of the esters of the 1-substituted-2-hydroxy methyl piperidines used in Examples 1 to 9, and 11, there may be employed the esters of other 1-substituted-2-hydroxy methyl piperidines, for instance, the esters of other 1-alkyl-, 1-phenyl lower alkyl, 1-phenyl-2-hydroxy methyl piperidines such as (1-benzyl piperidyl-2)-methyl benzilate, (1-ethyl piperidyl-2) methyl diphenyl acetate, (1-n-propyl-piperidyl-2) methyl mandelate, or the ester of α -chloro diphenyl acetic acid with 1-methyl-2-hydroxy methyl piperidine.

In place of diphenyl acetylchloride used as reactive acid derivative in Example 12 for esterifying 1-methyl-2-hydroxy methyl piperidine methiodide, there may be employed other carboxylic acids as they are mentioned hereinabove, or reactive derivatives of such acids, for instance, their bromides, their anhydrides, their mixed anhydrides, for instance, with alkyl carbonates, aryl carbonates or aralkyl carbonates.

In place of the 1-methyl-2-hydroxy methyl piperidine methiodide used for reaction with the acid chloride as described in Example 12, there may be employed other quaternary 1-substituted-2-hydroxy methyl piperidinium compounds such as the methosulfate of 1-methyl-2-hydroxy methyl piperidine, the methochloride of 1-methyl-2-hydroxy methyl piperidine, the methosulfate of 1-ethyl-2-hydroxy methyl piperidine, the ethosulfate of 1-methyl-2-hydroxy methyl piperidine.

Likewise, in place of 1-methyl-2-chloro methyl piperidine methobromide used for reaction with potassium benzilate as described in Example 13, there may be employed other quaternary 1-substituted-2-halogeno methyl piperidinium compounds such as 1-methyl-2-bromo methyl piperidine methochloride, 1-ethyl-2-bromo methyl piperidine ethobromide, 1-n-butyl-2-chloro methyl methochloride, 1-alkyl-2-chloro methyl methobromide, 1-methyl-2-bromo methyl methobromide.

In all these reactions and with all these different starting materials the procedure is followed as it is described in the preceding examples.

In place of methyl and ethyl iodide, methyl and ethyl bromide, and dimethyl sulfate as used in the preceding examples, there may be employed other quaternizing agents such as benzylbromide, diethyl sulfate, other alkyl or aralkyl halogenides, such as iso-propyl iodide, n-butyl iodide.

Especially valuable spasmolytic compounds of low toxicity and high spasmolytic activity are the benzilic acid esters of 1-alkyl-2-hydroxy methyl piperidine methohalides or methosulfates.

The new esters of quaternary 2-hydroxy methyl piperidinium compounds are administered orally, parenterally, or rectally. The preferred mode of administration is oral administration in the form of liquid or solid preparations, such as tablets, pills, dragees, powders, capsules, solutions, emulsions, suspensions, dispersions, or in any other suitable form.

In the case of powders, fine uniform dispersion of the

active compounds together with a usual carrier throughout said powder is of importance. Such a fine dispersion can be achieved by intimately mixing and milling the active compound, for instance, in a ball mill with a solid pulverulent extending agent to the desired degree of fineness or by impregnating the already milled, finely powdered, solid carrier with the active compound in water or with a solution thereof in a suitable organic solvent and then removing the water or solvent.

A fine dispersion of the active compound in water, sirup and the like can also be brought about by emulsifying said compound with the aid of a dispersing or emulsifying agent.

When preparing tablets, pills, powders, and the like solid preparations, the commonly used carriers and diluting agents, binders, and the like tabletting adjuvants are employed, such as sugar, lactose, starch, pectin, bolus alba, stearic acid, magnesium stearate, and as binders gelatin, gum arabic, methyl cellulose, carboxy ethyl cellulose, yeast extract, agar, tragacanth, and others. It is, of course, understood that any of the tabletting materials conventionally used in pharmaceutical practice can be employed provided there is no incompatibility with the active compound.

Injectable preparations and suppositories for rectal administration may also be prepared.

Of course, many changes and variations in the starting materials and reactants, in the solvents used, in the reaction conditions, temperature, pH-value of the reaction mixture, duration, in the methods of working up, isolating, and purifying the reaction products, and the like may be made by those skilled in the art in accordance with the principles set forth herein and in the claims annexed hereto.

We claim:

1. The carboxylic acid ester of a quaternary 2-hydroxy methyl piperidinium compound of the formula

X is an acyl group selected from the group consisting of the benzoyl, diphenyl acetyl, α -cyclohexyl phenyl glycoloyl, mandeloyl, and α -chloro diphenylacetyl group;

5 R1 is a member selected from the group consisting of hydrogen, alkyl of 1 to 8 carbon atoms, phenyl, and phenyl lower alkyl;

R5 is lower alkyl; and

An is a member selected from the group consisting of halogen and the alkyl sulfate group $-\text{SO}_4\text{R}_6$, wherein R6 is lower alkyl.

2. The benzilic acid ester of 1-methyl-2-hydroxy methyl piperidinium methosulfate of the formula

3. The benzilic acid ester of 1-n-butyl-2-hydroxy methyl piperidinium methiodide.

4. The benzilic acid ester of 1-n-octyl-2-hydroxy methyl piperidinium methobromide.

5. The benzilic acid ester of 1-alkyl-2-hydroxy methyl piperidinium lower alkohalide, its alkyl having 1 to 8 carbon atoms.

6. The benzilic acid ester of 1-methyl-1-alkyl-2-hydroxy methyl piperidinium methosulfate, its alkyl having 1 to 8 carbon atoms.
